CLOCKCASE

Alan W. Duncan, Oak Park, Ill., assignor to Sears,
Roebuck and Co., Chicago, Ill., a corporation
of New York

Application May 19, 1953, Serial No. 25,104

Term of patent 14 years

(Cl. D42—7)

To all whom it may concern:

Be it known that I, Alan W. Duncan, a citizen of the United States, residing in Oak Park, county of Cook, and State of Illinois, have invented a new, original, and ornamental Design for a Clockcase, of which the following is a specification, reference being had to the accompanying drawing, forming a part hereof.

Fig. 1 is a front elevational view of a clockcase embodying my new design;

Fig. 2 is a side elevational view thereof;

Fig. 3 is a fragmentary rear elevation thereof,

Fig. 4 is a bottom plan view of the base thereof, taken from the position indicated by the line 4—4 of Fig. 1,

Fig. 5 is a fragmentary sectional view taken substantially along the line 5—5 of Fig. 1, and

Fig. 6 is a fragmentary sectional view taken substantially along the line 6—6 of Fig. 1.

I claim:

The ornamental design for a clockcase, as shown.
